Warren D. House
His ATTORNEY.

UNITED STATES PATENT OFFICE.

CHARLES M. KEMPER, OF KANSAS CITY, MISSOURI.

CAR-DOOR MECHANISM.

Application filed April 7, 1922. Serial No. 553,418.

To all whom it may concern:

Be it known that I, CHARLES M. KEMPER, a citizen of the United States, residing at Kansas City, in the county of Jackson and

5 State of Missouri, have invented a certain new and useful Improvement in Car-Door Mechanisms, of which the following is a specification.

10 My invention relates to improvements in car door mechanisms.

It relates particularly to doors for grain cars.

15 A further object of my invention is to provide novel means for sealing the edges of the door when the latter is closed.

Still another novel feature of my invention is the provision of novel means for retaining the door in proper vertical alinement when in the closed position.

20 A further object of my invention is to provide a mechanism of the kind described which is simple, cheap to make, which is strong and durable and not liable to get out of order.

25 The novel features of my invention are hereinafter fully described and claimed.

In the accompanying drawings, which illustrate the preferred embodiment of my invention,

30 Fig. 1 is an elevation of a portion of a car body provided with my improved mechanism, portions being broken away.

Fig. 2 is a horizontal section on the line 2—2 of Fig. 1.

35 Fig. 3 is an enlarged vertical sectional view on the line 3—3 of Fig. 1.

Fig. 4 is an enlarged horizontal section on the line 4—4 of Fig. 1.

40 Fig. 5 is an enlarged vertical sectional view on the line 5—5 of Fig. 1.

Fig. 6 is a vertical sectional view on the line 6—6 of Fig. 4.

Fig. 7 is a horizontal sectional view, enlarged, on the line 7—7 of Fig. 1.

45 Similar reference characters designate similar parts in the different views.

1 designates a car body provided with a side doorway having jambs 2 and 3.

Attached to the inner side of the jamb 3

50 is a vertical channel plate 4, between the flanges of which the jamb 3 is located, and the outer flange of which is wedge-shaped and spaced apart from the outer side of the jamb 3 and which forms a seat for sealing the adjacent vertical edge portion of a main door 5, which is supported at its upper end

by rollers 6 mounted in a horizontal tubular guiding support 7, having a slot 8 in its lower side through which the upper end of the door extends.

60 The right vertical edge portion of the door 5 has fitted over it a vertical channel shaped plate 9, Figs. 2 and 7, the inner flange of which has a portion spaced apart from the inner side of the door. Transverse bolts 10 extend through the door and through the flanges of the channel plate 9. Respectively mounted on the inner ones of said bolts 10 are spacing rings 11 adapted to respectively enter notches 12, provided in 70 the vertical edge of the outer flange of the channel plate 4. The inner flange of the plate 9, when the door is closed, engages the inner side of the wedge-shaped outer flange of the channel plate 4, and draws 75 the door tightly against said flange.

76 The left vertical edge portion of the door 5 is provided with a vertical plate 13, doubled upon itself and embracing the inner and outer sides of the door. The doubled 80 portion of the plate 13 is adapted to enter between a vertical angle plate 14 attached to the jamb 2 and an angle plate 15 also secured to the jamb and having a portion spaced apart from the plate 14, Fig. 4, thus 85 forming a seat to receive the plate 13 when the door is closed. Extending through the plates 15 and 14 and into the jamb 2 are horizontal bolts 16, on which are respectively mounted spacing rings 17 adapted to 90 respectively enter notches 18 which are provided in the vertical edge of the plate 13.

95 The rings 17 and 11 serve to hold the door in vertical alinement when the door is in the closed position. The notches 12 and 18 are preferably inwardly converging, so as to engage and guide the rings 11 and 17 respectively.

100 For forcing the door 5 to and from the closed position, it has secured to it one end of a horizontal rack bar 19 provided in its upper edge with teeth 20 adapted to be engaged by a double acting pawl 21 pivoted to an upright lever 22, which is pivoted by a horizontal bolt 23 to the car body 1.

105 When the pawl is in the position shown in solid lines in Fig. 1, and the lever is oscillated, the rack bar 19 and door 5 will be forced to the closed position. By disposing the pawl 21 in the position shown in 110 dotted lines in Fig. 1, and oscillating the lever 22, the door is forced to the open posi-

tion. For guiding the end of the rack bar 19 which is distant from the door 5, there may be rotatably mounted on the outside of the body 1, in a housing 24 secured to the body, a roller 25 which supports the lower edge of the rack bar 19.

The door 5 may be provided with an auxiliary door 26 hinged thereto. For locking the door 26 and the door 5 in the closed position with the use of but a single locking pin, there is provided a hasp 27, pivoted by a horizontal bolt 28 to the outside of the door 5 and which is adapted to receive therethrough at its lower end a staple 29 secured to the door 5 at the outside thereof. When so engaged, the upper end of the hasp 27 engages the outside of the auxiliary door 26. A hasp 30 is pivoted to the jamb 2 by a staple 31 and is adapted to receive therethrough and to lockingly engage the staple 29 at the inner side of the hasp 27. A pin 32 is adapted to be removably fitted in the staple 31 at the outer side of the hasp 27. The pin 32 may be sealed in the usual manner by a wire 33 extending through the pin and engaged by a lead seal 34, Figs. 1 and 3.

To open the door 5, the seal 34 and wire 33 are removed from the pin 32, after which the pin is removed from the staple 29, following which the hasps 27 and 30 are disengaged from the staple 29. The pawl 21 is then moved to the position shown in dotted lines in Fig. 1. Upon oscillating the lever 22, the rack bar 19 and the door 5 will be forced to the open position.

Upon swinging the pawl 21 to the position shown in solid lines in Figs. 1 and 2, the door 5 will be forced to the closed position, shown in Figs. 1 and 2, and in 4 and

7, at which time the plate 9 will engage the outer wedge-shaped flange of the plate 4, thus drawing the door 5 tightly against the latter, and the plate 13 will fit tightly between the plates 14 and 15, and the inside lower portion of the door will also fit tightly against the body of the car.

I do not limit my invention to the structure shown and described, as many modifications, within the scope of the appended claims, may be made without departing from the spirit of my invention.

What I claim is:—

1. In a car door mechanism, a car body having a door jamb, two vertical plates, fixed spacing rings between said plates, the inner plate being attached to said jamb, bolts extending through said plates and respectively through said rings for attaching said plates to said jamb, and a door 55 slideable on said body and having a vertical edge portion adapted to enter and fit snugly between said plates, said edge portion having notches adapted to respectively receive said rings when the door is closed, 60 substantially as set forth.

2. In a car door mechanism, a car body having a door jamb, a vertical plate secured to said jamb and having a vertical flange provided with notches, a door slideable on said body, a vertical plate secured to the inner side of said door adapted, when the door is closed, to engage the inner side of said flange, and members fixed between the last named plate and said door adapted to 70 enter said notches respectively when the door is closed, substantially as set forth.

In testimony whereof I have signed my name to this specification.

CHARLES M. KEMPER.
